UNITED STATES PATENT OFFICE.

WENDELIN VÖLKER, OF WIESBADEN-SONNENBERG, GERMANY.

AUTOMATIC MEANS FOR LUBRICATING PUMPS.

1,084,769.

Specification of Letters Patent.

Patented Jan. 20, 1914.

Application filed May 1, 1911, Serial No. 624,398. Renewed November 28, 1913. Serial No. 803,602.

To all whom it may concern:

Be it known that I, WENDELIN VÖLKER, a subject of the German Emperor, and resident of Wiesbaden-Sonnenberg, Germany, have invented certain new and useful Improvements in Automatic Means for Lubricating Pumps, of which the following is a specification.

In order to be able to employ economically frigorific machines also in smaller industries such as for instance in butcheries, manufactories of sausage, wine cellars, dairying farms, hospitals, sanatoriums, hotels, restaurants, coffee houses, confectioners' shops 10 and so on and to introduce them into these branches, the compressors of the frigorific machines must preferably be simplified in such a manner that a small consumption of force and a simple manipulation are obtained.

In the actually employed compressors for frigorific machines in which the cold is produced by the aid of ammonia, carbonic acid, sulfurous acid or a similar carrier for cold, 25 the piston rod offers a drawback in that owing to its alternating motion the cold carrier constantly escapes to the outside and evaporates. Besides the precipitate thus formed is gradually introduced into the machine. It follows from all this that the machine does not remain at the height of its output and that the cold carrier must be replaced rather often. Besides the piston rod 30 wears out more in its middle part than at the ends whereby the tightness of the stuffing box is difficult to ascertain which is only possible by strongly tightening the packing sleeve of the stuffing box. This tightening causes a certain braking action which in 35 small compressors absorbs a relatively high percentage of the motive power. It is for this reason advantageous to inclose the crank shaft of the compressors of smaller frigorific machines in a closed casing which at the same 40 time may be employed as the suction chamber. This arrangement allows of the piston rod proper, as well as the cross head and the cross head guides being dispensed with as the piston may be directly connected with 45 the crank shaft by means of the connecting rod. The crank shaft requires tightening only on one side and only performs a rotary motion in the tightening means so that 50 nearly no leak can occur. Besides this kind of packing only absorbs a small amount of force. As readily seen this arrangement

does away with all the drawbacks cited above. Besides quite an important simplification of the working is obtained by the fact, that a single charge of oil allows of 60 all movable parts of the compressor being lubricated in a continuous and automatic manner during the space of months.

The present invention is based on the particulars cited above.

The accompanying drawing, given by way of example shows one form of embodiment of the device and in this drawing: Figure 1 is a cross section of a compressor; Fig. 2 is a top plan view of a detail of same.

The oil *b* contained in the oil collector *a* in which a certain excess of pressure reigns enters through the control cock *c* and the small pipe *d* the crank shaft of the compressor at *e* which crank shaft for the purpose of 70 conveying the oil has been provided with a bore opening out at *f* on the crank pin. A part of the oil escaping from this crank pin falls on the bottom of the crank casing or carter *g* and from there is transmitted by 75 the lubricating rings *h* to the bearings *i* of the crank shaft. Another part of said oil is whirled around by the rotation of the crank and mixed with the gas entering through the suction passage *k*, lubricates the piston 80 pin *l*, the suction valve *m* and the cylinder walls *n*. The oil mixed with compressed gas passes through the delivery valve *o* and the pipe *p* into the oil separator *r* formed of a corresponding number of pipes *q*. On the 85 walls of this separator the oil is separated from the compressed gas and collects, because it is heavier than the gas in the lower part of the oil collector *a* in readiness to begin again the cycle. An oil filter may also 90 be mounted into the oil collector. The compressed gas escapes through the tubular extension *s* branched on the oil collector and is conveyed for the purpose of its liquefaction into a condenser and from here into a 95 vaporizer where it yields its cold. The carrier finally enters again in a gaseous form 100 the crank casing *g* through the suction tube *k* and again begins the already described cycle.

Having now fully described my said invention, what I claim and desire to secure by Letters Patent, is:

In combination, a cylinder, a crank case communicating therewith, a crank shaft 110 mounted in the crank case, said crank shaft having an oil duct, a piston in the cylinder,

2
a suction valve located in the head of the piston to permit of oil passing upwardly through the piston and cylinder, a pitman connecting the piston and crank shaft, a delivery valve in the head of the cylinder, the crank case having a gas inlet between the bottom of the piston and the crank shaft, an oil receptacle located above the plane of the crank case having a gas outlet and an oil outlet, a duct connecting the head of the cylinder and the upper end of the oil receptacle, an oil separator supported above

the gas outlet and comprising a plate and a plurality of depending tubes, a pipe communicating with the oil outlet and the duct in the crank shaft, and a regulating valve in the said pipe.

In testimony whereof I have hereunto set my hand in presence of two witnesses.

WENDELIN VÖLKER.
